UNITED STATES PATENT OFFICE.

HOMER C. WOODBURY, OF PROVIDENCE, RHODE ISLAND, ASSIGNOR TO JOHN SCHEMINGER, JR., OF PROVIDENCE, RHODE ISLAND.

CIRCUIT-CONTROLLING APPARATUS.

1,388,541.

Specification of Letters Patent. Patented Aug. 23, 1921.

Application filed February 13, 1919. Serial No. 276,849.

To all whom it may concern:

Be it known that I, HOMER C. WOODBURY, a citizen of the United States, residing at Providence, in the county of Providence and State of Rhode Island, have invented certain new and useful Improvements in Circuit-Controlling Apparatus; and I do hereby declare the following to be a full, clear, and exact description of the invention, such as will enable others skilled in the art to which it appertains to make and use the same.

This invention has for its object improved mechanism for automatically controlling the circuit of an electric motor, or other translating device, to perform certain work in accordance with a variable demand for such work. It is designed primarily for use in connection with a rotary hydrocarbon burner in which organization a motor is used to operate the burner and the invention herein-after described comprises convenient arrangement of circuit controlling devices whereby the burner is put into or out of operation in accordance with temperature changes influenced by the burner. Its use, however, is not limited to this particular art, but it is capable of use in many other organizations as will be apparent to one skilled in the art.

30 A thermostatic device, capable of movement in response to changes of temperature, effects the closing of the circuit of an electro-magnetic relay, the latter operating to open and close the motor circuit as well as to control its own circuit. The switching arrangement under the control of the relay causes circuits to be made and broken in a definite sequence and by a novel combination of switch and operating elements to be herein-after described in detail.

The accompanying drawings, forming a part of this specification, illustrate a practical embodiment of the invention.

In these drawings:

45 Figure 1 is a diagrammatic representation of the invention, showing its relation to the circuits which it controls and by which it is controlled;

50 Fig. 2 is a plan view of the electro-magnetic circuit controlling device;

Figs. 3 and 4 are respectively side and end elevations of the same;

Fig. 5 is a detail view of the pawl and ratchet switch actuating mechanism;

55 Fig. 6 is a detail view of the rotary, cylin-

drical switch for the motor circuit, the contact fingers of which are shown in dotted lines;

Fig. 7 is a view of the ratchet disk, carrying a second switch element for controlling 60 the circuit of the electro-magnetic actuating mechanism;

Figs. 8 and 9 are detail views showing the component parts of said last named switch;

Fig. 10 is an assembled view of the two 65 switches, mounted on their common supporting shaft, and

Fig. 11 is a sectional view on the line 11—11 of Fig. 7.

Referring now to these drawings, M is a 70 motor, or other translating device, the circuit of which it is desired to control. It is assumed that current for operating the motor is supplied from any suitable supply mains which form no part of the present invention. 75

The entire circuit controlling mechanism of this invention is conveniently mounted upon a panel or supporting plate P, with binding-posts or terminals for all of the circuit connections, arranged so as to be readily accessible. 80

Included in the motor circuit, the connections for which to the panel board are numbered 1 and 2, is a rotary contact switch S, so 85 arranged that it may be operated to make or break the circuit of the motor M. The rotating element of this switch comprises a cylinder, the peripheral surface of which is divided into diametrically opposite insulating and conducting areas, the latter being electrically connected. Resilient contact fingers or brushes d and d¹ engage the periphery of the movable elements of the switch at diametrically opposite points and 90 are either separated by insulation or electrically connected, depending upon the position occupied by said movable element. The transition points on the switch are arranged (see Fig. 6) so as to effect a quick making 100 or breaking of the circuit. This is accomplished by providing an abrupt step on the periphery between areas of contact and insulation. The switch S is mounted upon and secured to a shaft A, but electrically insulated therefrom, in order to effectually prevent the relatively heavy currents of the motor circuit from coming into contact with any other part of this circuit controlling mechanism. The shaft A is mounted for ro- 105 110

tation in bearings *a* and *b* rigidly supported upon the base plate or panel *P*. The outer bearing *a* is in an overhanging arm of a supporting element *L*, the extent of the overhang being sufficient to give clearance to all switch and actuating mechanism mounted upon the shaft. These details are clearly shown in Figs. 3 and 4.

The shaft *A* also carries a ratchet disk *D*, by means of which rotary motion may be imparted to the said shaft. To produce this motion the following elements are combined: An electro-magnet *E* is mounted upon the base-plate *P*, being held in position by bolt connection with an upright arm *f* of a metallic supporting frame *U*. An armature *F* is pivotally supported at one end of the magnet upon a spring tongue *G*, which normally acts to hold the armature away from the pole-face of the magnet. A vertical extension or lever *H*, is secured to the armature, and is provided at its upper end with a bale-like pawl *K* to engage and operate the ratchet disk *D*. The pawl is held in engagement with the ratchet by pressure of one end *K*¹ of the pawl loop, against a backwardly bent portion *k* of the armature extension *H*. The usual adjustable stop in the nature of a screw *N* with lock-nut is provided to limit the backward movement of the armature.

The electro-magnet when energized will produce a vibratory movement of its armature *F*, and extension *H*, which movement will transmit rotary motion to the shaft *A* through the pawl and ratchet mechanism in a manner readily apparent. This motion of the shaft *A* resulting from energization of the magnet *E* would continue as long as the magnet circuit remains closed, with resultant alternate opening and closing of the circuit of the motor *M*, were no provision made for limiting the operation to that desired, namely, opening or closing the motor circuit. To limit the operation of the relay magnet, a second rotary switch is employed to secondarily control the circuit of the magnet in the manner hereinafter described. This switch is of disk-like form and mounted upon the shaft *A* upon which is also mounted the ratchet disk *D* and rotates in unison therewith. It consists of a circular contact plate or disk *R*, which may be cut or stamped into the configuration shown in Fig. 9, having the bent up portions *r* and *r*¹ and a segmental insulating disk *R*¹ secured thereto. Spring-pressed fingers *e* and *e*¹ cooperate with the movable element of the switch. These fingers are supported from and in electrical contact with the binding posts 3 and 4. In assembling this switch, the insulating disk is adjusted to the face of the contact disk *R* and by a partial rotation is interlocked with the upturned portions *r*, *r*¹ of the same, affording thus, a contact

surface presenting abrupt steps between conducting and insulating portions of the switch. The brushes or fingers engaging the same will pass smoothly over the areas of insulation or contact and in passing from one to the other the step will insure a desirable rapid making or breaking of the circuit. The disk *R* is not insulated from the shaft *A* and in tracing the circuits controlled by the switch, the said shaft and its supporting elements are to be included in the circuit of the electro-magnet *E*. The relative proportions of exposed insulation and contact areas of the switch are such that by rotation of the switch through an angle of approximately 90°, the relation of the contact fingers or brushes *e*, *e*¹ will be reversed, that is, the brush which previously rested on a contact surface, will after the indicated movement, rest on an insulating area, and the brush which rested on insulation, will engage a contact surface. This amount of angular displacement of the switch *Q* insures a movement of the switch *S* sufficient to cause it to either make or break the circuit which it controls. Associated with brushes *e* and *e*¹ is a thermostatic or equivalent element *T* having a pointer or tongue *t* which moves in response to changes in temperature to engage one or the other of the fixed contact points *t*¹ or *t*².

Each of these contact points is electrically connected to one of the brushes *e*, *e*¹; *t*¹ being connected to *e*¹ and *t*² with *e*. The fixed end of the thermostatic element is connected permanently with one terminal of a primary or secondary battery *B* of sufficient capacity to properly energize the electro-magnet *E*. The opposite terminal of the battery *B* is electrically connected with one end of the winding of the magnet *E*, the other end of said winding being in electrical connection with the limiting stop *N* of the magnet armature in the usual manner. A shunt connection *V* is provided for the magnet *E*, which is of advantage in reducing the sparking between the points of making and breaking of the magnet circuit, due to the vibrating of its armature. The operation of the circuit controlling device will now be apparent.

Referring to Fig. 1 the condition of the several circuits is as follows: The circuit of the motor or other translating device *M* is interrupted at the switch *S*. The thermostat *T* makes contact at *t*¹ which connects with the brush *e*¹. Since the latter rests on an insulating area *R*¹ of the disk switch the circuit of the electro-magnet *E* is also interrupted and the controlling device remains inactive. Upon a change in temperature, however, the thermostat *T*, moving automatically in response to such change, may swing its pointer *t* into engagement with the contact *t*². Current from the battery *B* can then flow through the thermostat to the

brush e by wire conductor connecting contact t^2 and brush e . Since this brush rests upon a conducting portion R of the disk switch current will pass through the switch 5 to the shaft A and by the metallic frame of the relay to the armature supporting tongue G , limiting stop N , electro-magnet E and thence back to the opposite pole of the battery. The relay being energized, a vibratory motion will be imparted to the lever 10 H , and through the pawl and ratchet mechanism the shaft A will be rotated to operate in sequence, the switch S and the disk switch. Contact is first established between 15 the brushes of the switch S and it is then necessary to stop the operation of the relay in order to maintain this circuit. This is effected through the disk switch. The contact finger e through which the magnet circuit 20 was established will have passed off from a contact area of the disk switch immediately after the motor circuit is made through the switch S . This results in breaking of the magnet or relay circuit and consequent stopping of the switch actuating 25 mechanism at the desired point. The second contact finger e^1 will have passed on to a contact area of its switch and the circuit controlling device will then be in readiness 30 to respond to changed conditions to restore the former position of the switches, when the thermostat registering such a change will move to again engage with the contact t^1 . Each closing therefore of the relay circuit by the thermostat making contact with either t^1 or t^2 will result in such operation 35 of the relay as will effect a change in the circuit of the motor M and thereupon the relay circuit will be broken to limit its further action until the thermostat engages the other contact whereupon the relay will be called upon to restore the motor circuit to its former condition.

Having thus described my invention, what 45 I claim as new and desire to secure by Letters Patent of the United States, is:—

1. In circuit controlling apparatus for regulating the supply of electric energy to a motor-operated hydrocarbon burner, the 50 combination of a rotary switch in the circuit of said motor, an electro-magnetic relay for operating said switch to effect the making or breaking of the motor circuit, a thermostat for controlling the relay circuit, and 55 a second rotary switch also operated by the relay to break the relay circuit, after the operation of making or breaking the motor circuit shall have been completed, substantially as described.

60 2. A circuit controlling device comprising a plurality of rotary contact switches mounted upon a common shaft and adapted to control as many independent electric circuits, a pawl and ratchet actuating mechanism for rotating said shaft, an electro-mag-

net for actuating said pawl and ratchet device; the circuit of said magnet being secondarily controlled by one of the rotary contact switches, and circuit controlling means responsive to temperature changes for primarily closing the magnet circuit to effect the operation of all the rotary switches in such sequence that the rotary switch of the magnet circuit will break this circuit only after such movement of the other switches 75 as is necessary to effect a change in the circuit which they control, substantially as described.

3. A circuit controlling device comprising a rotary contact switch for controlling the 80 making or breaking of a motor circuit, a shaft upon which said switch is carried, a ratchet disk also mounted upon said shaft, a spring-pressed pawl adapted to engage said disk and transmit motion thereto, an electro-magnet having a vibratory armature for 85 operating said pawl, a second rotary contact switch mounted upon said shaft and adapted to turn with the ratchet disk; the areas of contact and insulation on said last named 90 switch being substantially equal, two contact areas of like extent being separated by insulation areas of similar extent, two resilient contact fingers engaging the surface of said switch at points separated by a distance corresponding to the length of one contact area, and automatic temperature controlled means for closing the magnet circuit through one of the contact fingers and 95 conducting element of the switch associated therewith, to operate the circuit controlling device to the extent of producing an angular displacement of the shaft carrying the rotary switches equal to an angle of approximately 90°, by which movement of the shaft 100 105 a change is made by the rotary switch in the motor circuit, followed by a breaking of the magnet circuit at the second rotary switch.

4. A thermostatically controlled electro-magnetic circuit controlling device including a motor circuit and rotary switch capable of operation to make or break said circuit, a shaft mounted in suitable bearings and carrying the movable element of said switch 110 but electrically insulated therefrom, a second rotary switch also carried by the shaft and so positioned thereon that the conducting areas of the two switches are relatively displaced by an angle of approximately 90°, two resilient contact fingers engaging the second rotary switch at separated circumferential points, a lead from each contact finger adapted to be connected at one terminal of a thermostat, the movable element of which 115 is designed to make contact with one or the other of these terminals, an electro-magnet the circuit of which is controlled by said second rotary switch, and pawl and ratchet mechanism operated by the magnet to pro- 120 125 130

duce a measured rotation of the shaft sufficient to operate the rotary switches to effect a desired change in the motor circuit and to break the magnet circuit through one set 5 of contacts on the second rotary switch and simultaneously establish another connection for the magnet through this switch to leave the circuit controlling mechanism in condition to be again actuated by completion of

the circuit including the last-named contact 10 by the thermostat, substantially as described.

In testimony whereof I affix my signature in the presence of two witnesses.

HOMER C. WOODBURY.
